UNITED STATES PATENT OFFICE.

ALBERT DÉSIRÉ THOMAS, OF PARIS, FRANCE, ASSIGNEE TO AUTOMATIC ELECTRIC COMPANY, OF CHICAGO, ILLINOIS, A CORPORATION OF ILLINOIS.

LINE-FINDER SWITCH.

Application filed August 31, 1921. Serial No. 497,274.

To all whom it may concern:

Be it known that I, ALBERT DÉSIRÉ THOMAS, a citizen of the Republic of France, and a resident of Paris, France, have invented certain new and useful Improvements in Line-Finder Switches (for which application was filed in France on June 17, 1920, No. 517,300), of which the following is a specification.

- 10 The present invention relates to an apparatus which hunts for a calling line in a semi-automatic or automatic telephone system and connects said line up to a selecting device.
- 15 Usually, this class of apparatus has only one movement, that of rotation, a circumstance which restricts the number of subscribers' lines that can be rapidly and efficiently hunted for by a single apparatus.
- 20 The present invention provides an apparatus with two movements, viz; that of lifting followed by one of rotation, these two movements being obtained by the action of interrupter springs operated by lifting and rotary magnets, thus dispensing with the need for an impulse generator.

25 The call seeker being provided with several contact banks—each for 100 subscribers' lines—is able to hunt for the subscribers' lines very quickly, since 20 steps (10 lifting and 10 rotary) suffice to connect the subscriber's line that is furthest away from the normal position of the seeker to the next switch which is permanently connected up with the call seeker.

30 The accompanying drawing illustrates the circuit of a call seeker with 200 lines. It will be understood that this number can easily be increased by adding contact banks, wipers and a relay for each bank added.

35 When the subscriber at the calling station takes down his receiver, the private contact of the calling line is connected by a line relay to the negative battery through the winding of the cut-off relay (contact 64).

40 The pilot relay connects (1) negative pole of the battery with the contact corresponding, in the bank of vertical contacts, to the row of horizontal contacts in which the calling line is situated (contact 55), and (2) earth to the wire 72, which energizes the relay C through the contacts 1, 2, 4 and 5. The relay C operates the lifting magnet E through the circuit: earth, con-

tacts 10, 9, 21, 20, 35, 34, 38, 37, 48 and 49. 55 The action of the interrupter springs 48 and 49 causes the magnet E to raise step by step the shaft carrying the wipers.

When the vertical wiper 50 reaches the contact connected to the negative pole of 60 battery, the relay D is energized and breaks the excitation circuit of the lifting magnet E, closing at the same time that of the rotary magnet F.

By an action similar to the lifting action, 65 the rotary magnet F causes the wipers to move forward horizontally. When one of the private wipers 61, 62 reaches a contact connected to the negative pole of battery 64, the relay corresponding to the wiper 70 in contact with the negative pole of battery is energized in the circuit: negative pole of the battery, winding 74, contact 64, wiper 62, winding of relay A, contacts 43, 42, 33, 32, earth. The relay A operates and 75 opens the energizing circuit of the magnet F at the contacts 9 and 10, at the contacts 1 and 2 opens the circuit of the relay C, closes the contacts 1 and 3, earths the private wiper through the contacts 7 and 8,— 80 which keeps the cut-off relay 74 energized—, closes a holding circuit for the relay A through its second winding at the contacts 11 and 12; and connects up the line wipers 67 and 68 to the wires 69 and 70, at its 85 contacts 14 and 15, 16 and 17. The calling line is thus connected up to the selecting device, which, through the energizing of its line relay in series with the caller's instrument, earths the wire 71 in order to 90 hold the relay A in its operated position. If the calling line is in another hundreds group, i. e. the line hunted for by the wipers 61, 65, 66, the relay B is then energized and connects the wipers 65, 66 to 95 the line 69, 70 over the contacts 24 and 25, 26 and 27. The relay C is slow-acting in order to keep the lead 71 earthed long enough to allow the relay of the selecting device to operate and to establish an earth 100 connection with the said lead.

When the relay C releases, it breaks the circuit of the relay D, which removes the blocking potential over the contact 55, and thus enables the calling lines in the same 105 row of contacts to be hunted for by another seeker. It completes the operating circuit through the contacts 28 and 29, to the next

call seeker of this group of call seekers and prepares the circuit of the release magnet through the contacts 35 and 36.

When the conversation is finished and the receiver at the calling subscriber's instrument has been hung up again the earth is disconnected from lead 71, thus enabling the relay A to release and thus to close the circuit of the release magnet at the contacts 9 and 10 (or 20 and 21 if the relay B is employed for communication). The release magnet operates and releases the shaft carrying the wipers. On reaching its normal position the shaft operates the springs 44 and 45, thus breaking the circuit of the release magnet.

I claim:

1. In a finder switch a plurality of wiper sets, groups and subgroups of calling lines to which said wipers have access, another wiper for determining in what group a calling line is located, a relay in said switch operable upon initiation of a call for controlling said switch to move the wipers to select the group of lines in which a calling line is located, a relay in said switch operated when the proper group has been selected for causing said switch to simultaneously hunt for a calling line in all subgroups of the selected group, and other relays in said switch one of which is operated when a calling line is found to extend the calling line to an idle trunk line.

2. In a telephone system, a finder switch having primary and secondary magnets and a plurality of sets of wipers, a starting relay adapted to control the primary magnet when energized, a primary test relay for shifting the control of said starting relay to said secondary magnet at the end of the primary movement, a secondary test relay for each wiper set, and circuits for said secondary test relays closed simultaneously by said primary test relay.

3. In a telephone system, a finder switch

having primary and secondary magnets and a plurality of sets of wipers, a starting relay adapted to control the primary magnet when energized, a primary test relay for shifting the control of said starting relay to said secondary magnet at the end of the primary movement, a secondary test relay for each wiper set, contacts on each test relay for connecting the line wipers of the associated set, test circuits each including a secondary test relay and the test wiper of the associated contact set, and contacts on said primary test relay for closing all said test circuits when the secondary movement begins.

4. In a finder switch having primary and secondary magnets and a release magnet, a primary test relay controlling said primary magnet, and a plurality of secondary test relays jointly controlling said secondary magnet and said release magnet.

5. In a finder switch, a primary test relay, a plurality of secondary test relays, a starting relay, and primary and secondary motor magnets controlled by all said relays jointly.

6. In a finder switch, a primary test relay, a plurality of secondary test relays, a starting relay, primary and secondary motor magnets, and a circuit for said primary magnet controlled by all said relays jointly.

7. In a finder switch, a primary test relay, a plurality of secondary test relays, a starting relay, primary and secondary motor magnets, and a circuit for said secondary magnet controlled by all said relays jointly.

8. In a finder switch, a primary test relay, a plurality of secondary test relays, a starting relay, primary and secondary motor magnets controlled by all said relays jointly, and a release magnet controlled jointly by said secondary test relays and said starting relay.

ALBERT DÉSIRÉ THOMAS.
